CLAIM

I claim the ornamental design for a pitcher handle for a handleset, as shown and described.

DESCRIPTION

FIG. 1 is an oblique side view of a first embodiment of a pitcher handle for a handleset showing my new design;
FIG. 2 is the right side view of the pitcher handle shown in FIG. 1, the left side view being a mirror image;
FIG. 3 is the front view of the pitcher handle shown in FIG. 1;
FIG. 4 is the top view of the pitcher handle shown in FIG. 1;
FIG. 5 is the bottom view of the pitcher handle shown in FIG. 1;
FIG. 6 is a cross sectional view taken along 6—6 of FIG. 2;
FIG. 7 is a cross sectional view taken along 7—7 of FIG. 2;
FIG. 8 is a cross sectional view taken along 8—8 of FIG. 2;
FIG. 9 is an oblique side view of a second embodiment of a pitcher handle for a handleset showing my new design;
FIG. 10 is the right side view of the pitcher handle shown in FIG. 9, the left side view being a mirror image;
FIG. 11 is the front view of the pitcher handle shown in FIG. 9;
FIG. 12 is the top view of the pitcher handle shown in FIG. 9;
FIG. 13 is the bottom view of the pitcher handle shown in FIG. 9;
FIG. 14 is a cross sectional view taken along 14—14 of FIG. 10;
FIG. 15 is a cross sectional view taken along 15—15 of FIG. 10; and,
FIG. 16 is a cross sectional view taken along 16—16 of FIG. 10.
